UNITED STATES PATENT OFFICE.

GEORGE LINTON CHRISTMAN, OF SWISSVALE, AND HAROLD BAXTER, OF WILKINSBURG, PENNSYLVANIA, ASSIGNEES TO WESTINGHOUSE ELECTRIC AND MANUFACTURING COMPANY, A CORPORATION OF PENNSYLVANIA.

LATCHING DEVICE FOR KNIFE-SWITCHES.

1,199,451.

Specification of Letters Patent. Patented Sept. 26, 1916.

Application filed February 5, 1914. Serial No. 816,808.

To all whom it may concern:

Be it known that we, GEORGE LINTON CHRISTMAN, a citizen of the United States, and a resident of Swissvale, in the county 5 of Allegheny and State of Pennsylvania, and HAROLD BAXTER, a subject of the King of Great Britain, and a resident of Wilkinsburg, in the county of Allegheny and State 10 of Pennsylvania, have invented a new and useful Improvement in Latching Devices for Knife-Switches, of which the following is a specification.

Our invention relates to circuit interrupters, and it has special reference to devices 15 for detachably latching the movable members of knife switches in place.

Our invention has for its object to provide a latching device which is efficient and simple in construction and which can be applied to knife switches of existing types 20 without any alteration in their structure.

Our invention can best be understood by reference to the accompanying drawings, in which—

25 Figure 1 is a view in side elevation of a knife switch equipped with our improved latching device, and Fig. 2 is a view in front elevation of such a switch.

Referring to the drawings, a knife blade 30 switch member 1 is pivoted at 2 to a terminal member 2^a on a base 3 and adapted to be moved into and out of engagement with contact members 4, in the usual manner. The member 1 and the contact member 4 are provided with holes which are 35 occupied by pivot pins 5 and 12, to be hereinafter described.

The latching portion of our device is 40 pivotally mounted upon the pin 5 and comprises a hook member 6 having a portion 7 which is adapted to engage the end 8 of the switch blade 1 and hold it in its closed position. The hook member 6 has a shoe 20 formed on the end nearest the engaging portion 7 and it is retained normally in its operative position by means of a pin 9 which is forced outwardly from the body of the member by a spring 10 and bears against a base portion 11 of the contact member 4.

50 We provide a device for withdrawing the member 6 and disengaging the member 1 from the contact member 4 that comprises an arm 13 which is pivotally supported upon the pin 12. The arm 13 is normally

held in the position shown in Fig. 1 by a 55 spring 15, that is coiled about the pin 12 and is held in place by a collar 21 having a projection 22 which is engaged by one end of the spring. An opening 17 may be formed in the free end of the arm 13, into 60 which a hook may be inserted for the purpose of opening the switch. The ring formed by the opening 17 may obviously be replaced by a hook, handle or other engaging means. At the opposite end of the tripping member 13 is a hammer-like striking head 18 that is adapted to engage the rear face 19 of the hook member 6.

When the switch is closed, the parts occupy the positions shown in Fig. 1. When 70 it is desired to open the switch, a hook is manually inserted in the opening 17 and given a downward pull to cause the head 18 to strike against the face 19 of the hook member 6 and thus effect such movement 75 of the member upon its pivot 5 as to free the end of the blade 1 and permit the switch blade to be pulled away from the contact member 4. When the switch is again closed, the corner 23 of the blade 1 engages the 80 shoe 20 of the hook member 6 to effect such movement of the member upon its pivot 5 as will permit the blade to be inserted between the jaws of the contact member 4. When the blade reaches its closed position, 85 the hook portion 7 is again in position to retain it in that position.

It is obvious that many changes may be made in the structure which we have described and shown without departing from 90 the intent and spirit of our invention, which is to be limited only by the scope of the appended claims.

We claim as our invention:

1. In a latching device for knife-blade switches, the combination with a latch pivoted on the stationary contact member of the switch and having a portion adapted to hold the switch blade in its closed position, and a pin spring-pressed outwardly 100 from the body of the latch and coöperating with the base of the stationary contact member to hold the latch yieldingly in its operative position, of means pivoted on the blade for causing the latch to release the blade. 105
2. In a latching device for knife-blade switches, the combination with a latch pivoted on the stationary contact member

- of the switch and having a portion adapted to hold the switch blade in its closed position, and a pin spring-pressed outwardly from the body of the latch and coöperating 5 with the base of the stationary contact member to hold the latch yieldingly in its operative position, of a spring-restrained striking member pivoted on the switch blade and adapted to engage the latch only when 10 the switch is to be opened.
3. In a latching device for knife-blade switches, the combination with a latch of substantially L-shape pivoted on the stationary contact member of the switch, said 15 latch having a portion on one of its arms adapted to extend over the end of the switch blade to hold it in its closed position and an enlarged portion on its other arm, and a pin spring-pressed outwardly from the 20 body of the latch to hold the latch yieldingly in its operative position, of a striking member pivoted on the switch blade and adapted to engage the enlarged portion of 25 the latch only when the switch is to be opened.
4. In a latching device for electric knife switches, the combination of a latch pivoted on the stationary contact member of the switch and having a portion adapted to hold the switch blade in its closed position, and 30 a pin spring-pressed outwardly from the body of the latch and coöperating with the base of the stationary contact member to hold the latch yieldingly in its operative position, said latch also having a shoe portion adapted to be engaged by the end of the blade when the switch is being closed, whereby the latch is rotated to permit the end of the blade to be engaged by the latch, with means mounted on the blade for causing 35 the latch to release the blade.

In testimony whereof, we have hereunto subscribed our names this 28th day of Jan., 1914.

GEORGE LINTON CHRISTMAN.
HAROLD BAXTER.
